UNITED STATES PATENT OFFICE

2,160,977

WRENCH

Harry W. Michalka, Rice Lake, Wis.

Application July 26, 1937, Serial No. 155,787
Renewed January 9, 1939

6 Claims. (Cl. 81—130)

My invention relates to improvements in wrenches, and the primary object thereof is to provide a wrench of the sliding jaw type equipped for quicker operation, as regards clamping and releasing a nut or other object, than wrenches as commonly constructed and particularly designed for easy operation to both clamping and releasing positions.

My invention is also particularly designed to provide a wrench capable of operation as above set forth and comprising few parts of simple inexpensive construction, readily assembled and disassembled for replacement purposes, and in which all worm and other slow acting drive parts are eliminated.

Other and subordinate objects, together with the exact nature of my improvements, will become readily apparent as the following description proceeds and upon reference to the drawing accompanying and forming a part of this specification.

In said drawing:

Figure 1 is a view in side elevation,

Figure 2 is a similar view illustrating the interior construction of the wrench and with parts showing in section,

Figure 3 is a view in rear elevation,

Figure 4 is a view in front elevation, and

Figure 5 is a fragmentary view in section taken on the line 5—5 of Figure 2 looking in the direction indicated by the arrows.

Referring to the drawing by numerals, my improved wrench, in its preferred embodiment, comprises, a substantially straight flat sided handle 1 terminating at one end in an enlarged flat head portion 2 provided with a stationary jaw member 3 projecting therefrom in the plane of the handle and offset laterally of the longitudinal center thereof. The head portion 2 is formed, in its outer end face, with a transverse, rounded open guideway 4 therein. A movable jaw member 5 is slidably mounted in said head portion 2 for movement into and out of clamping relation to the fixed jaw member 3 and by means of a base flange 6 fitting into said guideway 4. The jaw members 2 and 5 and the outer face of the head portion 2 may be inclined in the usual manner and for the usual purpose well understood and not requiring explanation herein. The guideway 4 may be extended under the base of the fixed jaw member 3, as indicated at 7, and the flange 4 of the movable jaw member 5 may be extended, as at 8, to provide adequate bearing surfaces for the jaw member 5. The handle 1 is provided with a chamber 9

extending throughout the greater portion of its length and opening at the head end of the handle, as indicated at 10, into the guideway 4 for a purpose presently seen. The chamber 9 is provided with a straight rear side wall 11 parallel with the longitudinal axis of the handle 1. A cover plate 12 countersunk in said handle, as indicated at 13, is removably secured to the handle by means of screws 14 taking into bosses 15 in the chamber 9 projecting from the 10 walls of said chamber.

The following mechanism is provided for sliding the movable jaw member 5 into and from clamping relation to the fixed jaw member 3.

A toothed pinion 16 is rotatably mounted in the chamber 8, on a stud 17, and at the head end of the chamber. The pinion 16 projects through the opening 10 into the guideway 4 and meshes with teeth 18 formed on the under face of the base flange 6. The pinion 16 is rotatable in either direction by means of a straight rack bar 19 disposed in the chamber 9 alongside of straight wall 11 thereof and provided at one end with teeth 20 meshing with pinion 16 and at its other end with teeth 21 adapted to interlock with similar teeth 22 on the inner face of said wall 11. It will be understood that the teeth 21 and 22 are adapted to lock the bar 19 against movement in a direction permitting releasing movement of the jaw 5. The arrangement of the pinion 16 is such that the rack end of said slide bar 19 is held in engagement thereby with the wall 11.

The other end of the slide bar 19 is urged toward interlocking engagement with the teeth 22 by means of a compression spring 23 mounted in a socket 24 in one of the bosses 15 and bearing against said end of the slide bar 19. The slide bar 19 is normally locked in interlocking relation and flat against the straight wall 11 by means of a locking member 25 comprising a bar engaging arm 26 and a manipulative arm 27. The locking member 25 is pivoted, intermediate the arms 26 and 27, in the chamber 9, by means of a pivot pin 28 with its manipulative arm 27 projecting through a slot 29 in the front side wall 30 of the handle 1. The bar engaging arm 26 is of sufficient length to cam the slide bar 19 against the side wall 11 and to frictionally interlock with said bar in this position of the latter. A tension spring 31 having its opposite ends connected to the arm 26 and one of the bosses 15, respectively, tensions the member 25 against movement into unlocking position. In the locking position of the member 55

25, the arm 27 thereof engages one end of the slot 29 and limits movement of the said member beyond locking position. The slot 29 is closed on the inside thereof by a plate 32 mounted by 5 means of a slot 33 therein on the arm 27 for movement therewith over the slot 29. A leaf spring 34 mounted on the pivot 28 of the member 25 and bearing against the plate 32 yieldingly engages the latter with the wall 30.

10 The slide bar 19 is provided with a button-like manipulating member 35 playing in a slot 36 formed in the wall 11. The head end of the chamber 9 is curved outwardly from the rack end of the slide bar 19, as at 37, to provide a fulcrum 15 point 38 behind said end and a clearance for said end, whereby said rod may be swung inwardly of the chamber 9 on said fulcrum point 38 and against the urge of the spring 23. During such swinging movement of said bar, the rack end of 20 the same is held in meshing relation with pinion 16, as will be clear. In the inwardly swung position of the bar 19, it may be moved endwise by manipulation of the member 35. In this connection, it may be stated that the opening 10 in 25 the head portion 2 is designed to accommodate the rack end of the bar 19 in its endwise movement.

In operating the wrench to clamping and unclamping positions, the locking member 25 is first 30 swung to unlocking position, against the urge of the spring 31, and for manipulation of the arm 27. The slide bar 19 may then be forced inwardly, for the purpose above set forth, by pressure exerted upon the member 35 and slid in the direction desired. Upon release of the member 35 and the arm 27, said bar 19 will be swung flat against the wall 11 under the combined action of the springs 31 and 23, the teeth 21 and 22 interlocked and the bar locked in the position into 40 which it has been moved. In the event that the arm 27 is not released, the spring 23 will function alone to interlock said teeth 21 and 22.

The foregoing constitutes a detailed description of a preferred embodiment of my invention 45 and it is believed that its operation and construction will be clear therefrom, without further explanation.

It is to be understood, however, that the present disclosure is illustrative rather than restrictive of the principles of my invention and that right is herein reserved to modifications of details described falling within the scope of the claims appended hereto.

50 55 What I claim is:

1. In a wrench, a handle, a stationary jaw on the handle, a movable jaw fitting said handle and slideable crosswise thereof toward and away from the stationary jaw, a rack slidably fitted in the 60 handle and susceptible of side motion, a pinion rotatably fitting the handle and in toothed engagement with the movable jaw and said rack, latching teeth formed in the handle and on the rack for separable engagement with each other on side swing of said rack, means within the handle for urging the teeth on the rack toward the teeth in the handle, and a locking trigger fitting

the handle and engaging the rack for holding it in a latching position.

2. In a wrench, a handle, a stationary jaw on the handle, a movable jaw fitting said handle and slideable crosswise thereof toward and away from the stationary jaw, a rack slidably fitted in the handle and susceptible of side motion, a pinion rotatably fitting the handle and in toothed engagement with the movable jaw and said rack, latching teeth formed in the handle and on the 10 rack for separable engagement with each other on side swing of said rack, means within the handle for urging the teeth on the rack toward the teeth in the handle, a locking trigger fitting the handle and engaging the rack for holding it in a 15 latching position, and means urging the trigger in locking position.

3. In a wrench, a handle, a stationary jaw on the handle, a movable jaw fitting said handle and slideable cross-wise thereof toward and away 20 from the stationary jaw, a rack slidably fitted in the handle and susceptible of side motion, a pinion rotatably fitting the handle and in toothed engagement with the movable jaw and said rack, latching teeth formed in the handle and on the 25 rack for separable engagement with each other on side swing of said rack, means within the handle for urging the teeth on the rack toward the teeth in the handle, and a fulcrum in the handle for holding the rack in engagement 30 with the pinion when the rack is swung.

4. The combination with a wrench of the character described having a handle, a fixed jaw, a jaw having a geared surface movable by the rotation of a geared pinion, a swingable and reciprocable rack carried in said handle, one end of said rack being geared and engageable with teeth in the handle for selective locking of the rack, of means for maintaining constant and cooperative engagement of the other end of the 40 rack with the pinion for driving same when the rack is swung.

5. The combination with a wrench of the character described having a handle, a fixed jaw, a jaw movable by the rotation of a geared pinion 45 meshing with one end of a swingable and reciprocable geared rack carried in the handle, the opposite end of said rack being also geared and engageable with teeth in the handle for selective locking of the rack, of a fulcrum formed in the 50 handle for cooperative engagement with the pinion end of said rack to prevent disengagement of the rack and pinion when the opposite end of the rack is swung.

6. In a wrench, a fixed jaw, a handle provided 55 with a chamber therein having a toothed wall, a movable jaw having a cogged surface slideable transversely of the handle, a pinion meshing with the cogged surface of said movable jaw, a manipulative bar having a pinion driving end, and a 60 toothed locking end for interlocking with the teeth of said wall, said bar being movable endwise of said handle for driving operation, and swingable laterally to move its locking end into and out of interlocking engagement with the 65 teeth on said wall.

HARRY W. MICHALKA.
